UNITED STATES PATENT OFFICE.

JAMES W. PIKE, OF LITTLE FALLS, NEW YORK.

CIRCULAR-KNITTING MACHINE.

SPECIFICATION forming part of Letters Patent No. 423,080, dated March 11, 1890.

Application filed August 13, 1888. Serial No. 282,530. (No model.)

To all whom it may concern:

Be it known that I, JAMES W. PIKE, of Little Falls, in the county of Herkimer and State of New York, have invented new and useful 5 Improvements in Circular-Knitting Machines, of which the following is a specification.

My invention relates to that class of knitting-machines which are provided with a revolving needle-cylinder, and in which the fabric is knit in the form of a circular web or tube.

The object of my invention is to improve the construction of the cam-rings which actuate the needles, whereby the cam-rings can 15 be readily attached and detached, and also to provide simple means whereby the cam-rings can be readily adjusted; also to improve the construction of the thread-guides.

The invention consists of the improvements 20 which will be hereinafter fully set forth, and pointed out in the claims.

In the accompanying drawings, consisting of three sheets, Figure 1 is a vertical sectional elevation of the upper portion of a 25 knitting-machine provided with my improvements. Fig. 2 is a fragmentary front elevation thereof. Fig. 3 is a top plan view of the machine. Fig. 4 is a horizontal section in line $x x$, Fig. 1. Fig. 5 is a vertical section of the 30 cam-rings and their support in line $x' x'$, Fig. 4. Fig. 6 is a fragmentary inside elevation of the cam-rings on an enlarged scale. Fig. 7 is a sectional elevation of one of the 35 adjustable standards whereby the cam-rings are supported. Fig. 8 is a perspective view of one of the thread-guides.

Like letters of reference refer to like parts in the several figures.

A represents the top or table portion of the 40 machine supported upon legs a.

B represents the revolving needle-cylinder supported upon the table A by an annular flange b and provided at its lower end with a downwardly-projecting sleeve b', arranged 45 in an opening b², formed centrally in the table A.

C represents an external gear-rim secured to the lower end of the sleeve b' of the cylinder B, and c represents a gear-pinion meshing with the gear-rim C and secured to the 50 upper end of a vertical shaft c', which is journaled in a bearing c², secured to the table A.

Motion is transmitted to the pinion c and needle-cylinder B from a driving-shaft c³ by bevel-wheels c⁴ in the usual manner. 55

The cam-cylinder which surrounds the needle-cylinder B is composed of a lower ring D', which is supported upon an annular frame d, and an upper ring D, which is bolted or secured to the lower ring. The rings D D' 60 are each provided on their inner surface with cams arranged opposite each other and forming a cam-race for the needles, the upper edge of the cam-race being formed by the cams on the upper ring D and the lower edge of the 65 cam-race by the cams on the lower ring D'.

d' represents the needles arranged between the cylinder B and the cam-cylinder and which are actuated by the latter in the usual manner. 70

The cam-rings D D' are each composed preferably of three sections e e' e² and f f' f², respectively, but a greater number of sections may be employed, if desired. The sections f f' f² of the lower ring D' are secured to the 75 annular frame d by screws f³ and dowel-pins f⁴, and the sections e e' e² of the upper cam-ring D overlap and break joint with the sections of the lower cam-ring and are secured to the latter by screws e³ and dowel-pins e⁴. 80 The meeting edges of these sections are cut obliquely, so as to cause the edges to overlap each other, and thereby prevent the needle-jacks from working into these joints and cause the parts to bind or break. 85

By constructing the cam-cylinder in sections the operator is enabled to readily replace a broken cam or a needle-jack or to substitute tuck for plain cams by simply removing one or more of the sections of one or 90 both of the cam-rings, as may be required, without removing or raising the entire cam-cylinder.

G represents posts or standards, upon which the annular frame d is supported by arms g, 95 having sleeves g', which fit snugly over the posts G, and which can be adjusted vertically thereon by nuts g², applied to the threaded portion of the standards. The posts G are secured with their lower ends to the table A. 100 Each sleeve g' is provided with a depending flat spring g³, secured to the sleeve g', and having a tooth g⁴, which engages in a notched rim g⁵, formed on the nut g². The springs g³

serve as gages when the nuts g^2 are turned for adjusting the cam-rings, and also lock the nuts g^2 after the parts are adjusted. This construction permits of a very fine and uniform vertical adjustment of the frame d on all of its supports without gaging or caliper-
ing the parts from the table to the frame d , as heretofore practiced. The same vertical adjustment is readily effected on each post 10 by turning each nut to the extent of the same number of notches.

H represents an annular frame which supports the thread-guides and encircles the upper portion of the needle-cylinder B , and 15 which is composed, preferably, of three sections $H' H^2 H^3$. The sections $H' H^2 H^3$ are secured to the upper cam-ring D by screws h , passing through vertically-elongated openings h' , formed in brackets h^2 , so as to be vertically 20 adjustable. Two of the brackets h^2 are preferably secured to each section of the supporting-frame H , and each section of the frame H is secured by these brackets to a corresponding section of the upper cam-ring D , so that it 25 can be removed with the same.

Each section of the supporting-frame H is provided with a series or group of thread-guides I , which encircle the upper ends of the needles d' . Fig. 3 of the drawings shows the 30 group of these guides attached to the section H^2 , while those of the sections $H' H^3$ are omitted.

As clearly shown in Fig. 8 of the drawings, each thread-guide I consists of a standard i , 35 secured to the supporting-frame H by a vertical screw-bolt i' , and a radial guide-plate i^2 , secured to the upper end of the standard i by a thumb-screw i^3 , passing through an elongated opening i^4 , formed in the guide-plate i^2 . 40 $i^5 i^6$ represent openings formed in the arms $i^7 i^8$ of the guide-plate i^2 , and through which the thread passes to the needles. It will thus be seen that all of the thread-guides I , arranged upon one of the sections of the supporting-frame H , can be simultaneously adjusted by means of the brackets h^2 , thereby 45 facilitating the uniform adjustment of the guides. The inner arm i^7 of each guide-plate i^2 can be adjusted vertically and radially toward and from the needles d' by means of the thumb-screw i^3 and slot i^4 , as well as laterally by swinging the standard on its screw-bolt i' . By this construction a great saving 50 of time is effected in adjusting the thread-guides, as it is not necessary to bend or twist the guides, as in the case with guides formed in one piece.

I claim as my invention—

1. The combination, with the needle-cylinder and a supporting-frame surrounding said cylinder, of a cam-cylinder composed of a 60

lower cam-ring secured to said supporting-frame and composed of a number of detachable sections, and an upper cam-ring, also composed of a number of detachable sections 65 and secured to the lower cam-ring, each ring being provided on its inner surface with separate cams forming a cam-race for the needles, substantially as set forth.

2. The combination, with the needle-cylinder, of a ring divided transversely into segmental sections and each of said sections supported independently of the others, and thread-guides attached to said ring-sections, substantially as set forth. 70

3. The combination, with the needle-cylinder and a cam-ring surrounding the same, of an annular frame surrounding the needle-cylinder, means whereby said frame is made vertically adjustable on said cam-ring, and 80 thread-guides secured to said annular frame, substantially as set forth.

4. The combination, with the needle-cylinder and a cam-ring surrounding the same, of an annular frame surrounding said needle-cylinder and composed of a number of independent sections, means whereby each of said sections is made separately adjustable on said cam-ring, and thread-guides secured to each section, substantially as set forth. 85

5. The combination, with the needle-cylinder, an annular frame surrounding said cylinder and composed of a number of sections, and thread-guides secured to said sections, of a cam-ring also surrounding said cylinder and 95 composed of a similar number of sections, each of which cam-sections carries one of the sections of said supporting-frame, substantially as set forth.

6. The combination, with the needle-cylinder and the annular supporting-frame H , composed of several independent sections, of brackets h^2 , secured to the frame H and provided with vertically-elongated openings, a cam-ring D , composed of a similar number of sections, and screws h , whereby the brackets h^2 are adjustably secured to the sections of the cam-ring, substantially as set forth. 100

7. The combination, with a needle-cylinder and a thread-guide-supporting frame, of a standard i , pivoted to the supporting-frame by a vertical screw-bolt, and a radial guide-plate i^2 , having thread-openings and adjustably secured to said standard by a thumb-screw i^3 and slot i^4 , substantially as set forth. 105

Witness my hand this 7th day of August, 1888.

JAMES W. PIKE.
